UNITED STATES PATENT OFFICE.

FREDERICK W. WHITEHOUSE, OF PELHAM, NEW YORK.

DESIGN FOR A FINGER-RING.

45,247.

Specification for Design.

Patented Feb. 10, 1914.

Application filed November 12, 1913. Serial No. 800,680. Term of patent 7 years.

To all whom it may concern:

Be it known that I, FREDERICK W. WHITEHOUSE, a citizen of the United States, residing in the town of Pelham, Westchester county, State of New York, have invented a certain new, original, and ornamental Design for Finger-Rings, of which the following is a specification, reference being had to the accompanying drawing, forming a part thereof.

Figure 1 is an elevational view of one side of a finger ring; and Fig. 2 is a like

view of the other side of the ring, showing my new design.

I claim:

The ornamental design for a finger ring, as shown.

In witness whereof I have hereunto signed my name in the presence of two subscribing witnesses.

FREDERICK W. WHITEHOUSE.

Witnesses:

ARTHUR GOUGH,
GEO. B. LITTLE.
